SOUND REPRODUCING DEVICE OF THE PNEUMATIC RELAY TYPE

Otto Kurt Kolb, Chiswick, London, and William John Rickets, Edgware, England, assignors to British Acoustic Films, Ltd., London, England, a British corporation

Application July 9, 1936, Serial No. 89,804
In Great Britain July 24, 1935

2 Claims. (Cl. 179—113)

In the art of sound reproduction it has been known that a current of air or other gas may be passed through a valve which is controlled and vibrated at acoustic frequencies by a member, 5 such as a gramophone stylus or the operative element of a telephone, such valve serving thereby to set up corresponding acoustic pulsations in the column of gas passing through it.

By directing such a modulated gas column or 10 stream through a suitable horn or like acoustic coupling means, the vibrations impressed on the gas column can be efficiently communicated to the surrounding atmosphere.

In order to control correctly and usefully the 15 flow of gas through a valve so acting, it is essential that the valve shall be retained normally in a partly open condition, in order that the half oscillations which it makes in one direction shall act to diminish the gas flow below its mean value, 20 whereas half oscillations in the opposite sense shall increase the gas flow above its mean value.

With such devices, however, a difficulty is experienced in that the relatively large volume of gas flow passing through the apparatus requires 25 considerable power for its maintenance. A second and more serious effect is that the passage of the large air current at silent periods or during the reproduction of weak sounds, causes a considerable amount of stray hissing or background 30 noise.

According to the present invention, the air or other gas used is passed through a single valve or two valves to which are applied two controlling motions, one a representation as faithful as possible of the actual sound vibrations to be reproduced, the second a motion which is proportional to the amplitude of the envelope curve of the series of sound waves applied to the apparatus, or to the averaged intensity of the sound passage 40 being reproduced.

In the drawing, Figs. 1 and 2 are vertical cross-sections of two embodiments of the invention, and Figs. 3 and 4 are diagrams of circuits which may be used with these embodiments. 45 Fig. 5 is a modification of Fig. 3.

In one form of the device which is indicated in Figure 1 of the accompanying drawing, a pneumatic control valve such as a grid or comb valve IV, vibrating laterally over a multi-slit aperture valve seat IS, is actuated electrodynamically, for example by attachment to a moving coil IM, which, in the example, has one winding IM1 which is traversed simultaneously by a phonic current representing the sound being reproduced as regards the actual amplitudes and wave form and

by an envelope current proportioned to the existing amplitude of the envelope or intensity curve of the sound. Two separate windings may be utilized, each individually carrying one of the currents referred to. This arrangement is 5 schematically shown in Fig. 5, the two windings being 70c and 70c¹, which may be windings of one moving coil. In this case, the grid or comb valve is normally positioned in the closed or practically closed position relative to the apertures 10 in the valve seat by a suitable controlling force applied, for example, by means of the suspensory ribbons or ligaments 111, 112, 113 and 114, and on the passage of the envelope current is opened 15 more or less proportionally to said current, so that at the fullest excursion of the valve its mean position corresponds to half closure.

The envelope current may conveniently be derived by drawing from the electrical sound reproducing channel at an appropriate point, a certain 20 proportion of acoustic or phonic current, by then rectifying this and passing it or a current controlled by it, for example by means of a thermionic valve, through one of the operating moving coil windings of the relay device, if necessary after 25 passing the rectified or controlled current through suitable amplifying and delay circuited devices of known kind.

In an alternative form of electrically operated apparatus according to the invention, the valve 30 of a type similar to that hereinbefore referred to may be attached to a moving magnetic armature constituting part of any known electro-magnetic form of telephone receiver movement. In this case, one or two operative windings of the telephone receiver carry the dual control currents hereinbefore referred to. An apparatus of this kind is indicated in Figure 2 of the appended drawing, in which a grid or comb valve 2V vibrating laterally over a multi-slit aperture valve seat 4 is connected to the reed armature 2R of a telephone receiver and to two suspensory ligaments 211 and 212. The reed armature is influenced by the electro-magnetic telephone system comprising two pole pieces 2T1 and 2T2 carried by a 4 horseshoe permanent magnet of known type. The operative windings of the telephone surrounding the two pole pieces carry the envelope current and the phonic current hereinbefore referred to. As in the previous example, the setting of the valve is normally in the closed position, and becomes more or less opened according to the amplitude of the envelope current. When one operative winding only is employed, either on the moving coil of an electrodynamic reproducer or 5

like part, or on the exciting winding of a telephonic electro-magnet used for actuating the valve of such an apparatus, the two control currents, that representing the sound as regards frequency and amplitude, and that representing the envelope curve or mean intensity of the sound are both passed simultaneously through the same winding by means of circuits, connections or couplings of the various kinds well known in the art.

The effect of the above described and equivalent devices constructed according to the invention is as follows:—

When a phonic electric current representing a sound passage to be reproduced by the device is passed through the apparatus and its auxiliary controlling means, there is applied to one of the valves controlling a compressed gas flow, two sets of vibrations, one representing the actual sound passage, the other representing changes in the mean intensity or maximum amplitude of the sound, in such a manner that when feeble sounds are being reproduced, or when silent passages occur, one or other of the valves utilized serves to close almost entirely the air passage through the valve system. Consequently, the large useless rush of air through the valve now generally present, is avoided, and disturbing background or hissing noise is reduced to a minimum. When sounds of larger amplitude are being reproduced, whichever valve is controlling the mean intensity or amplitude factor of the sound being reproduced opens more widely the air passage through the valve system, and a volume of gas flow is permitted of such a value that it may be modulated by the larger sound vibrations involved.

The pneumatic supply to the valve system may be provided by the use of a source of air or gas pressure, such as a small pump, working into a first storage chamber, the pressure in which may vary and feeding through a reducing valve of known sensitive type into a secondary storage chamber containing the air or other gas of substantially steady pressure, from which the said gas passes through the amplifying valve system to a suitable horn or like sound emitting element.

Figs. 3 and 4 illustrate circuit arrangements which may be used with the above described devices.

Referring to Fig. 3, herein an amplifier 1A is connected to the control grids of the two valves or multi-electrode electrical discharge devices 1V1 and 1V2 in the ordinary way, so that the fluctuations in its phonic current output are applied as potential changes to these two control grids. Valve 1V1 is connected to the transformer 1TW which deals with the actual phonic current as regards wave form. The anode of valve 1V1 is connected through the primary of this transformer 1TWP to a positive pole of supply and the secondary of the same 1TWS is connected to the operative coil of the unit driving the pneumatic valve V as shown in the two Figs. 1 and 2. This coil is lettered 1OC and is equivalent to the moving coil 1M of Fig. 1 or the telephonic windings 2T1 and 2T2 of the driving arrangement in Fig. 2. The valve 1V2 has its anode connected to the primary winding 1TAP of the transformer 1TA which is connected as regards its secondary 1TAS to the rectifier 1R, which may be of any suitable type but is shown as a set of bridge connected dry contact rectifiers, the output of which is connected also

across the coil 1OC. The transformer 1TA thus deals with the amplitude or envelope current applied to the same moving element 1OC. A condenser 1C is connected as shown in series with the secondary of transformer 1TW for the purpose of preventing the passage of direct current through this winding 1WS.

It will be obvious that with this arrangement phonic current passes through the condenser 1C from the transformer 1TW and rectified current simultaneously passes with this phonic current through the operating coil 1OC which, being embodied in the drive unit, either in the form of a moving coil or telephonic winding, suitably moves to open the air valve to a wider mean position with increasing current amplitude, when loud passages are being reproduced in the manner set forth in the specification.

Fig. 4 represents a variant of an arrangement for carrying out this effect, and in this case the amplifier 8A may, at a suitable stage, have tappings which connect directly to a rectifier system 8R and an output connection through the grid condenser 8GC which is connected to the control grid of one valve 8V1 which in this arrangement controls both the wave form and amplitude current passed through the operating coil 8OC. The rectifier 8R has its output connected to a potentiometer resistance 8P which bears a sliding contact to which the control grid of the valve 8V1 is connected, it may be through the grid resistance 8GR. A bias battery 8BB connects the cathode of the valve 8V1 to one termination of the potentiometer resistance as shown, and the potential difference due to this battery is impressed in series with that due to the fall of potential in potentiometer 8P onto the control grid of valve 8V1. The anode of the valve 8V1 connects through the transformer primary winding 8TWP and through the operating coil 8OC to a positive source of supply, whilst the secondary winding 8TWS of this transformer is connected as shown through the condenser C to the same winding. In this case also, two currents, one the anode current flowing to valve 8V1 and the alternating current set up in transformer 8TW are simultaneously impressed on the operating coil.

Having now particularly described and ascertained the nature of our said invention, and in what manner the same is to be performed, we declare that what we claim is:—

1. A sound reproducing device of the pneumatic relay type having a single valve of the multi-port type, a fixed seating cooperating therewith to control the flow of a gas column from substantially zero value to a maximum, means for varying the valve opening proportionally between a position of closure and a half open position as the amplitude of the reproduced sound is varied, and means for superimposing the vibrations representing the sound wave-form on said amplitude movement.

2. A sound reproducing device of the pneumatic relay type having a valve of the multi-port type, a seat cooperating therewith to control the flow of a gas column from substantially zero value to a maximum, means for varying the valve opening proportionally between a position of closure and a half open position as the amplitude of the reproduced sound is varied, and means for superimposing the vibrations representing the sound wave form on said amplitude movement.
